FREDERICK C. OVERBURY, OF NEW YORK, N. Y., ASSIGNOR TO FLINTKOTE MANUFACTURING COMPANY, OF RUTHERFORD, NEW JERSEY, A CORPORATION OF NEW JERSEY.

WEATHERPROOF COVERING.

1,104,998.

Specification of Letters Patent.

Patented July 28, 1914.

Application filed March 18, 1913. Serial No. 755,133.

To all whom it may concern:

Be it known that I, FREDERICK C. OVERBURY, a citizen of the United States, and a resident of New York, in the county of New York and State of New York, have invented certain new and useful Improvements in Weatherproof Coverings, of which the following is a specification.

This invention has relation to water-proof and weather-proof coverings for the roofs and sides of buildings which are exposed to the weather. It has been heretofore proposed to use, as a covering, shingles made of fabrics or other suitable material treated with a water-proofing substance. Where such shingles are made of such material as a woven fabric or felt, treated with a water-proofing substance, they are more or less flexible and lack the stiffness and rigidity of wooden shingles, so that they are in danger of being blown from the roof or sides of the house or of working loose from the fastenings, due to the continual movement and contraction and expansion of the exposed portions of the shingles. Where such shingles are secured in place by nails or other fastenings passed through the exposed portion of the shingle into the foundation, the contraction and expansion of the shingle enlarges the nail holes so that each hole permits the rain to leak through. Roofing shingles made of felt or fabric and treated with water-proofing substances, such as asphaltum, pitch and the like, so as to be properly water and weather proof, are brittle in cold weather, so that when they are bent they are apt to break or crack along the line of bend so as to expose the fabric to the elements, in consequence of which they soon become valueless or are unfit to be used.

One of the objects of the present invention is to provide a shingle, which may be used as a substitute for wooden shingles (which are becoming scarcer every year), which will produce the same effect in appearance as wooden shingles, and which when secured in place render leaks practically impossible. It consists of a flexible weather and water-proof flexible shingle or other covering having a doubled-back portion connected by a hinge portion with the main body portion, the coating being stretched at the hinge, so that, when the

doubled-back portion is manipulated, the coating thereon will not crack or break. 55

In carrying out my invention, I employ as a base a suitable material such as wool felt. Sheets of this material are thoroughly impregnated with a water-proofing material, such as pitch or asphaltum or compounds containing the same or equivalent materials which have a relatively low melting point. The faces of the sheet are coated with layers of asphaltum, pitch or other water-proof and weather-proof material which have a relatively higher melting point and which are capable of withstanding the heat of the sun and the elements. This sheet may be cut into blanks of the desired width and somewhat longer than the length of the ultimate shingle to be produced. The blank is then heated so that it is capable of bending easily and one end of the blank is folded back upon the blank on a transverse line, the length of the folded portion being preferably substantially equal to or a little greater than that portion of the shingle which will be exposed when it is laid. Assuming that each shingle will have six inches of its length exposed, the folded end will be approximately six, or six and one-half inches in length, so that it will underlie that portion of the shingle which is to be exposed. While the blank is still in a warm and pliable state, the doubled-under portion 85 may be bent back and forth across the line of the fold and is then folded back permanently. By this method, the felt is stretched more or less near the outer exposed portion of the fold, and the coating is also stretched while it is warm and pliable, so that when the bend is completed there are no cracks, the bend forming as it were a hinge. 90

On the accompanying drawings,—Figure 1 represents in longitudinal section a blank 95 which is to be made into a shingle. Fig. 2 represents a similar section and illustrates the completed shingle. Fig. 3 is an enlarged section, showing pictorially as well as may be a shingle blank with the folded end turned back so as to lie in the same plane as the remainder of the shingle. Fig. 4 is a similar section illustrating the bend. Fig. 5 illustrates the method of laying the shingle. Fig. 6 represents a longitudinal 105 section of a roof showing the shingles laid.

Fig. 7 represents in plan view a portion of a roof with the shingles thereon. Fig. 8 shows the invention embodied in sheet roofing having rectangular tabs or projections which resemble shingles.

5 α indicates the base of the roofing shingle which, as said, is preferably made of felt and which is saturated or impregnated with any of the water-proofing compounds now 10 commonly in use by roofing manufacturers. Both faces of the shingle are covered with coatings b formed of any suitable pitch-like weather-proof and water-proof material which will not melt when exposed to the 15 heat of the sun and which will withstand the action of the elements. This material may comprise any suitable pitch or bitumen or asphaltum which is now employed by roofing manufacturers in the manufacture of 20 prepared roofings. If desired, the facing material may be colored by the addition of a suitable pigment. The shingle blanks, having approximately the relative dimensions as shown in Fig. 5, are cut from the 25 sheet. The main body of the shingle is indicated at 10. The blank is somewhat longer, as previously stated, than the ultimate shingle to be produced, the excess length being indicated at 11. The blank is 30 then heated at or near the portion thereof indicated by the dotted line in Fig. 1, and the portion 11 is folded back on the under side of the blank, as shown in Fig. 2, to form a bend or hinge 12. While the facing 35 material is still soft and pliable, the doubled-under portion 11 may be folded back and forth on the line of the bend and then be bent permanently into place as shown in Fig. 2. After the portion 11 is doubled under, the coatings set, and that portion of the 40 coating outside the bend remains in its elongated condition. When the doubled-under portion is bent out straight again as shown in Fig. 3, it will be seen that the felt is more 45 or less stretched and somewhat thickened as shown at 13, the outer facing or coating is elongated as indicated at 14 (and in some cases it may be separate from the felt), and the inner facing or coating is more or less 50 corrugated as indicated at 15 without the presence of cracks or breaks in the outer facing. When the shingle is cold and even when the atmospheric temperature is relatively low, the doubled-under end may be 55 moved back and forth without cracking the outer facing. Consequently the shingles may be laid as shown in Fig. 5; that is to say, the doubled-under portion may be straightened out so as to be attached to a 60 foundation 20 by nails or other fastenings 21 passed through the doubled-under portion 11 of the shingle. Thereafter the main body of the shingle may be swung upwardly and its upper edge secured in place by nails 65 or fastenings 22, all as shown in Figs. 5 and

6. The courses of shingles are laid upwardly so that, when the roofing is complete, as shown in Fig. 4, the nails or fastenings are all covered by imperforate portions of the shingles so that there is no danger whatever of a leak through the roof or siding.

70 As a result of the method which I have herein described, I have provided a water-proof and weather-proof shingle, the exposed portion of which is double the thickness of the remainder of the shingle, the doubled-under portions being connected by a hinge, as it were, with the main body of the shingle, so that, in low temperature conditions, the doubled-under portion of the shingle may be swung about the line of the bend without breaking or cracking.

75 While I have described the invention as being particularly embodied in a shingle 85 and have described the method of making shingles, it will be understood that siding boards or clapboards may be made by the same method, and that also roofing strips (either plain or serrated) may be provided 90 with a hinge formed as herein described.

In Fig. 8 I have shown strip or sheet roofing, provided with tabs or projections 22. These tabs or projections have doubled-under ends connected with the bodies thereof 95 by bends, joints or hinges made as herein described, so that the outer layer at the bend is elongated or stretched and permitted to set in elongated or stretched condition.

If desired, the facing or coating on the 100 inner face of the blank may be scraped off along the line on which the doubled-under portion of the shingle is to be bent. Instead of treating each shingle blank separately, it is evident that the sheet of felt, 105 after being saturated and then coated by the usual instrumentalities, may be drawn through a folding appliance so as to double back an edge portion of the sheet, after which the shingles may be cut from the 110 sheet by a suitable cutter. The bending may be accomplished while the coating is still soft and pliable. If it is too cold, I pass the sheet through or in proximity to a heating medium. For instance, the sheet may 115 be drawn through a bath of hot water, or else the sheet, along the line of the subsequent bend, may be heated by gas jets or by any other suitable means. If desired, the sheet could be of double width, both side 120 edges doubled under, the sheet slit longitudinally through the middle and the shingles separately cut or severed from the two strips thus formed. Where shingles are made as herein described with the hinge 125 and the doubled-back portion, they are packaged and shipped in that condition to the customer.

130 It has been observed that the adhesion of the plastic coatings or layers is so great

- throughout the surface of the fabric or felt that there is no perceptible slipping of said layers, there being merely an elongation or stretching of the outer layer at the 5 joint or bend. As a result, when the plastic layers set, there is a permanent elongation of the coating on one side of the joint and a permanent compression or corrugation on the other side of the joint.
- 10 Having thus explained the nature of my said invention and described a way of making and using the same, although without attempting to set forth all of the forms in which it may be made or all of the modes 15 of its use, what I claim is:
1. A water-proof weather-proof flexible covering formed of a water-proofed base and coatings of water-proof weather-proof material, and comprising a body portion 20 and a doubled-back portion, said portions being connected by a hinge formed of the covering itself, and the exposed coating of the hinge set in a stretched and elongated condition, and the under or back coating 25 in a compressed condition, so that the doubled-back portion may be bent back and forth without breaking the coating at the hinge.
2. As a new article of manufacture, a 30 water-proof weather-proof flexible shingle formed of a water-proofed base and a pitch-like coating of weather-proof material, and comprising a body portion of suitable length and breadth and a doubled-back portion to 35 underlie the exposed portion of the shingle, the pitchlike coating at the bend being permanently set in an elongated or stretched condition.
3. As a new article of manufacture, a 40 water-proof weather-proof flexible shingle formed of a water-proofed base and pitch-like coatings of weather-proof material, and comprising a body portion of suitable length and breadth and a doubled-back portion to 45 underlie the exposed portion of the shingle, and a hinge connecting said portions, the exposed coating of said hinge being set in a stretched and elongated condition, and the interior coating being set in a compressed or corrugated condition. 50
4. A water-proof weather-proof flexible covering formed of a base of felt impregnated with water-proof material and having a coating or facing of a pitch-like weather-proof substance, and comprising a body portion, a doubled-back portion, and a connecting hinge portion, the coating or facing of the hinge portion being set in a stretched and elongated condition so that the doubled-back portion may be manipulated without cracking said stretched or elongated coating or facing of the hinge. 55
5. The herein described method of making thickened weather-proof and water-proof coverings, which consists in heating the covering to render the water-proof and weather-proof facing thereof relatively soft and pliable, then bending the covering back on itself to form a thickened edge portion, thereby elongating the exposed plastic coating at the bend and permitting the coating 60 to set in an elongated condition. 65
6. The herein described method of making thickened weather-proof and water-proof shingles having a pitch-like weather-proof facing or coating, which consists in softening the coating to make it pliable, bending back the end of the shingle and stretching and elongating the softened coating to form a hinge, and then permitting the coating to set in an elongated or stretched condition, so that the doubled-back portion may subsequently be manipulated without cracking or breaking the hinge. 70 75
- In testimony whereof I have affixed my signature, in presence of two witnesses.
